UNITED STATES PATENT OFFICE.

OSKAR FISCHER, OF BERLIN-WILMERSDORF, GERMANY.

TYPEWRITING-MACHINE.

1,392,135.

Specification of Letters Patent. Patented Sept. 27, 1921.

Application filed March 19, 1914. Serial No. 825,776.

To all whom it may concern:

Be it known that I, OSKAR FISCHER, a citizen of the German Empire, residing at Berlin-Wilmersdorf, in the Kingdom of Prussia, Germany, have invented certain new and useful Improvements in Typewriting-Machines; and I do hereby declare the following to be a full, clear, and exact description of the invention, such as will enable others skilled in the art to which it appertains to make and use the same.

My invention relates to improvements in typewriting machines, and more particularly in typewriting machines in which the type carrier consists of a rotary type wheel having the types arranged about its circumference, and in which key controlled electromagnets are provided for rotating the type wheel with one of the types in printing position and throwing the same against the platen, and also if desired for shifting the carriage for letter spacing. For this purpose by depressing the key levers electric contacts are made by means of which the circuits including the electromagnets for rotating and throwing the type wheel are closed. One of the objects of the improvements is to so construct the key lever mechanism and the electric rotating and throwing means, that the machine can be operated at high speed. A further object of the improvements is to regulate the rotary and throwing movements of the type wheel in such a way, that the characters printed by the type wheel are not blurred and are perfectly clear. With these and other objects in view my invention consists in so constructing the key lever mechanism and the electrical rotating and throwing means, that all the operations of the machine, which in machines of ordinary construction are performed by the downward and upward strokes of the key levers, are performed by the downward stroke of the key levers, so that it is not necessary to release a depressed key lever before another one is depressed. Furthermore my invention consists in so constructing the contact making devices for the rotating and throwing electromagnets, that by depressing a key lever the rotating and

throwing electromagnets are successively thrown into operation, while they are simultaneously thrown out of operation.

By thus constructing the typewriting machine the operation is made convenient, the fingers, which in machines of ordinary construction are moved from one key to the other one, can rest on the keys. In the operation of the machine the weight of the hand is alternately shifted from one finger to another one, and instead of moving the hand from one key to the other one in my improved machine only slight movements are necessary which are performed exclusively by the fingers, and which can be performed at greater speed and with less strain, and which are performed with great accuracy even if the writer's eye is not directed to the keys, because the fingers are always placed on the same keys.

In constructing a typewriting machine of this kind it is necessary that the electromagnets remain energized until the type wheel has struck the platen. If the energizing circuit were interrupted before this moment, the type wheel would begin its rotary return movement prior to printing the desired character, or the type wheel would not come into contact with the platen, and in any case printing would not be performed with sufficient force. However, when the type wheel strikes against the platen all the movable parts come to rest, so that the contacts can not be opened any more, because for doing this the contact breaking parts must be in motion.

In my improved machine this difficulty is overcome by providing intermediate members which transmit the movement of the keys to the contacts, and which are disconnected from the key levers by elements controlled by the electromagnets while the keys are moving downward or are being depressed. Thereby the contacts are moved into circuit breaking positions independently of the key levers, and the type wheel throwing or printing electromagnet is thrown into operation by closing two contacts disposed in series. One of the contacts is closed by depressing the keys and together

with the contact of the circuit of the rotating electromagnet, while the other one is closed by the armature of the said rotating electromagnet, so that both electromagnets are successively thrown into operation, while they are simultaneously thrown out of operation. Thereby the energizing circuits remain closed until the type strikes against the platen, or they may even be broken slightly thereafter, and yet the circuits are broken in such a way, that the parts for setting and throwing the type wheel, and also the means provided for shifting the carriage for letter spacing and the ribbon feed mechanism are returned into inoperative or normal positions immediately after printing and even if the key lever is still in depressed position. Thereby the printing electromagnet returns into initial position without any delay, the speed of writing is increased, and the character which has been printed can not be blurred, which would be the case if the type wheel were rotated backward and into initial position before it is rocked away from the platen. My improved machine consumes little electric energy, because only short current impulses are necessary for operating the same.

My invention also relates to other improvements all of which will hereafter be explained in detail and particularly pointed out in the appended claims.

While in describing the invention reference will be made to a particular embodiment thereof, I wish it to be understood that my invention is not limited to the construction shown in the drawings, and that various features thereof may be embodied in machines of different types.

For the purpose of explaining the invention an example embodying the same has been shown in the accompanying drawings, in which the same letters of reference have been used in all the views to indicate corresponding parts. In said drawings—

Figure 1, is a longitudinal section of the machine,

Fig. 2, is a plan view thereof partly in section,

Fig. 3 is a vertical section of the frame carrying the type wheel,

Fig. 4 is a plan view of the mechanism for shifting the type wheel,

Fig. 5, is a partial longitudinal section showing the mechanism for throwing the type wheel against the platen,

Fig. 6, is a rear view of a part of the machine showing the mechanical means for operating the type wheel,

Fig. 7, is a plan view of the parts shown in Fig. 5 for imparting throwing or letter printing movement to the type wheel,

Fig. 8, is a detail view showing the lower part of the type carrier and its frame,

Figs. 9 to 12, show the means for making

the contacts controlling the electromagnets of the machine,

Figs. 13 and 14, are detail views showing novel means for operating the contacts,

Fig. 15, is a vertical section of the type wheel and the upper part of the type wheel shaft and showing means for readily mounting or dismounting the type wheel,

Fig. 16, is a sectional view showing means for locking and releasing the carriage at the ends of its paths,

Fig. 17, is a plan view of the parts shown in Fig. 16, and

Fig. 18, is a diagram showing the electrical connections of the machine.

Referring to the example illustrated in the drawings, my improved machine consists of a base plate 1, a medial plate 2, and a top plate 3. The top plate and the base plate are connected with each other by pillars 4. Above the top plate the carriage is mounted on suitable guide rails, and on the carriage the platen 5 is mounted in any known or preferred way.

The type carrier is provided by a type wheel 6 on which three sets of types are provided, and which is removably mounted on a shaft 7. Ordinarily the types of the upper set are in printing position. If it is desired to print a sign from a type of the medial or lower set, the type wheel is shifted. For this purpose the shaft 7 is longitudinally shiftable within a sleeve 8, rotation of the shaft relatively to the sleeve being prevented by means of a collar 11 secured to the shaft and provided with a lug 11¹ moving in a longitudinal slot 11² of the sleeve. Between the said collar and a bushing 10 secured to the upper end of the sleeve 8 a spring 9 is interposed which normally forces the shaft 7 and the type wheel 6 downward and with the upper set of types in printing position relatively to the platen.

The shaft 7 is mounted on a rocker plate 12 on which two pillars 13 and 14 are mounted which are connected with each other at their upper ends by a plate 15. To the middle part of the said plate a disk 16 is secured which provides the upper race of a ball bearing the lower race of which is formed on the bushing 10. At its lower end the shaft 7 is formed with a reduced portion 17 which has rotary movement in a corresponding socket provided in a short bolt 18. The said bolt has longitudinal shifting movement within a sleeve 19 which is secured to the rocker plate 12 by means of a flange 20. Normally longitudinal movement of the bolt 18 relatively to the sleeve 19 is prevented by means of the spring 9 acting through the shaft 7. Within a transverse bore made in the shaft 18 a pin 21 is provided which projects with both ends through longitudinal slots 22 of the sleeve 19. By depressing one of the shift key

levers 25 or 26 the type wheel is shifted through the intermediary of rocking frames 27 or 28 and links 29 or 30, the shifting movements being such, that when depressing 5 the key lever 26 the medial set of types is brought into printing position. The frames 27 and 28 have rocking supports respectively in bearings 31, 32 and 33, 34. The rear ends of the key levers 25, 26 are located below pins 35, 36 secured to the rocking frames 27 and 28 respectively. At their lower ends the links 29 and 30 are jointed to the inner arms of the frames 27 and 28 respectively, and at their upper ends they 15 are jointed to the transverse pin 21.

The rocker plate 12 provides the armature of a printing or throwing electromagnet 37, or as shown in Figs. 5 and 6, it is secured to the armature 38 of the said electromagnet. 20 The type wheel shaft 7 and the rocker plate are in the form of a bell crank lever which has a rocking support by means of pivots 39 and 40 mounted in bearings provided in pillars 41 and 42.

25 The downward stroke of the rocker plate 12 is limited by cushions 43 and 44 made from felt or some other suitable material (Figs. 5 and 6). In order that the movement of the rocker plate be as noiseless as 30 possible two further felt cushions 47 and 48 and two springs 49 and 50 are secured to the said plate. When the rocker plate is being attracted by the electromagnet 37, the springs 49 and 50 strike at first on the cushioning members 43 and 44, whereupon they 35 are bent and get into engagement with the cushioning members 47 and 48 by means of which the stroke of the rocker plate is finally limited. In order that also the upward stroke of the rocker plate be limited 40 in a noiseless way, two inclined springs 51 and 52 are secured to the top face of the rocker plate, which springs are disposed in position for engagement by the cushioned 45 inclined surfaces of adjustable stop members 53 and 54.

Before the type wheel strikes against the platen, and preferably while the key levers are being depressed, the type wheel must 50 be turned to the right or left at such an angle, that the character or letter corresponding to the depressed key is in position exactly opposite to the printing point. This is effected by the following mechanism: 55 To the lower end of the sleeve 8 which incloses the type wheel shaft 7 a pinion 55 is secured which is in mesh with a toothed sector 57 having a rocking support on an axis 56. Rocking movement is imparted to 60 the said sector by either one of two electromagnets 58 and 59 the armatures 60 and 61 of which are connected by a flexible tension element such as a wire 62 and screws 64 and 65, the said tension element being 65 also connected with the sector by the screw

63. By means of the electromagnet 58 left hand rocking movement is imparted to the type wheel through the intermediary of the wire 62, and by the electromagnet 59 right hand movement is imparted thereto, and in 70 each case both armatures are rocked, because they are positively connected with each other and with the toothed sector. For returning the sector into medial position a spring 66 is coiled around the axis 56 which bears 75 with both ends on a pin 67 secured to the rocker plate 12. To the sector a pin 68 is secured which is likewise located between the ends of the spring 66. In order that the type wheel be not rocked beyond its 80 medial position after printing, the sleeve 8 is formed below the pinion 55 with a collar 69 which is formed with a notch adapted to be engaged by a pawl 70. The said pawl must be thrown into releasing 85 position each time before one of the armatures 60 or 61 can rock the sector 57, and the type wheel 6. The mechanism provided for this purpose will be described herein-after. 90

The rotary movement of the type wheel to the right or to the left for setting one of the types in printing position must be interrupted as soon as the type to be printed is in printing position. In my improved 95 machine this is done by means of a pair of stop arms 71 secured to the type wheel shaft 7 and adapted to strike against a pin which is operated by the key lever being depressed and shifted thereby into the path 100 of one of the stop members. It will be understood, that each of the key levers operates a pin of its own, and all the pins are mounted on a circle which is concentric to the type wheel shaft. Therefore each 105 pin is adapted to arrest the type wheel with a particular type of each set in printing position. The construction of the stop mechanism so far described is known in machines which are provided with a type 110 carrying sector, and it is modified in my improved machine in order to adapt the same to a machine in which the types are provided on a type wheel having rotary movements in both directions. In a machine 115 of this class the known mechanism can not be provided, because it would be necessary to arrange the stop members on a complete circle, in which case it would be difficult to connect the same with the key levers. 120 Therefore I have modified the construction as follows:

To the sleeve 8 which incloses the type wheel shaft 7 two arms 71 are secured which coöperate with radially disposed setting 125 members 72 and 73. The said setting members have rocking supports on a semi-circular rod 74, and their number is equal to the number of the types provided in each set on the type wheel and to the number of 130

key levers corresponding thereto. When the type wheel is turned to the left the left hand arm 71 strikes against the first, third, fifth, seventh, etc. setting member 72, and when 5 the type wheel is turned to the right the right hand arm 71 strikes against the second, fourth, sixth, etc., setting member 72. In the machine shown in the drawings the key levers of the lower series are connected with 10 the first, third, fifth, etc., setting member, and the key levers of the upper series are connected with the second, fourth, sixth, etc., setting member.

The connection between the key levers and 15 the setting members is shown in Figs. 1 and 2. As shown in the said figures, the key levers 76 are mounted on bifurcated pillars 77, and at their rear ends they are provided with sockets 79 which are engaged by the 20 lower ends of vertical rods 78 engaging with their upper ends disks 82 of radially mounted bell crank levers 80, having rocking supports on a common semi-circular rod 81. The vertical arms of the said bell crank 25 levers are bifurcated and between the bifurcated portions arms 83 and springs 83¹ acting thereon are mounted. When depressing a key lever, the corresponding arm 83 is moved toward the shaft of the type wheel, 30 and it rocks the coöperating setting member 72 or 73 about its fulcrum provided by the rod 74 and into position for stopping engagement with one of the stop arms 71. In Fig. 1 the stop arm 71 is shown in rocked 35 position.

The horizontal arms of the setting members 72 and 73 bear on pairs of rings 84, 85 and 86, 87, as is shown in Figs. 1, 9, 10, 11, and 12. When depressing a key and rocking 40 the corresponding setting member 72 or 73, either the rings 84, 85 or the rings 86, 87 are forced downward. The said rings are guided within each other and within a stationary ring 88 which incloses the movable 45 rings and rises from the base plate 2. They are formed with projections so as to provide longitudinal strips 84', 85', 86', and 87', between which bails 89, 90, 91, and 92 are jointed. The said bails have rocking supports 50 on a common shaft 93 mounted in brackets 94 and 95, and they provide guides for the rings 84, 85, 86, and 87. The strips 84', 85', 86', and 87' are notched at their lower ends in such a way, that the two outer rings 84 55 and 85 both act on contact levers 96 and 97, while the inner rings 86 and 87 act on contact levers 98 and 99. The levers 96, 97, 98, and 99 have rocking supports in brackets 100, 101, 102, and 103, and they are acted 60 upon by springs 104, 105, 106, and 107, which tend to lift the rings 84, 85, 86, and 87 into engagement with the horizontal arms of the setting members 72 and 73. The levers 96, 97, 98 and 99 have contact springs 108, 109, 65 110, and 111 secured thereto which are lo-

cated with their contact points below contact screws 112, 113, 114, and 115. When depressing a key always two contact springs 108 and 109, or 110 and 111 are moved upward, whereby at first the springs 109 or 111 close a circuit which includes the rotating electromagnets 59 or 58 respectively, while the circuit of the printing electromagnets 37, which includes the springs 108 and 110, is closed later, as will now be described. 70 75

The armatures 60 and 61 of the rotating electromagnets are equipped with contact making arms 116 and 117 respectively, to which the contact screws 112 and 114 are secured. If one of the armatures 60 or 61 is rocked, the corresponding contact screw 114 or 112 is likewise rocked and moved downward and toward the coöperating contact spring 110 or 108 which is located below the same. 80 85

Simultaneously therewith or slightly before, the contact spring 108 or 110 is moved upward and toward the coöperating contact screw. Therefore the circuits of the printing electromagnets which are controlled by the contacts 112, 108 and 114, 110 respectively are closed after the circuits of the rotating electromagnets which are controlled by the contacts 109, 113 and 111, 115 are made. 90 95

The object of the construction of the contact making devices coöperating with the printing electromagnets is the following: As has been explained above, in view of the rapid operation of the machine it is desirable, that the type wheel rotating movement and the printing movement be performed as far as possible simultaneously, the rotary movement however being completed before the type wheel strikes against the platen. If the angle at which the type wheel is to be turned is but small, printing may be performed more rapidly, than in such cases where the said angle is comparatively large. 100 105 By constructing the contact making devices in such a way, that the contacts for the printing electromagnet are made by the rocking movements of the armatures of the rotating electromagnets, printing can not be premature. As the rotating electromagnet is already moving when the printing electromagnet is being energized, it arrives at the end of its movement before the printing electromagnet has completed the printing 110 115 operation. Under any circumstances the contact for the printing electromagnet must be made so late, that the type wheel can complete its rotation before printing is completed, and for this purpose the contact making devices must be set according to the maximum angle at which the type wheel can be turned. However in such cases in which the rotation is completed comparatively early, the circuit of the printing electromag- 120 125 130

net is closed unnecessarily late, so that in such cases the velocity of printing is unnecessarily small, though apart from this consideration, it would be possible to print so much the sooner, the smaller the angle of rotation of the type wheel is. To avoid this disadvantage, my machine is constructed as follows: As has been described above, by each operation of the setting members 72 and 73 two of the rings 84, 85 and 86, 87 are depressed. As is best shown in Figs. 13 and 14 one of the said rings is made at its top in the form of a half screw-thread. Therefore it is forced downward by the setting members 72 and 73 a distance which is different in all the setting members, and which corresponds to the angle of rotation of the type wheel. As the movement of the ring is transmitted to the coöperating contact spring 108 or 109, the said spring is moved toward the coöperating contact screw a greater or less distance. Furthermore the strokes of the contact screws are different, because the stroke of the armature of the rotating electromagnet varies according to the angle at which the type wheel is turned. The parts are so arranged, that where the stroke of the rotating armature is small the stroke of the contact spring is increased accordingly, and vice versa. Therefore, when the type wheel is turned at a small angle, the contacts of the circuit including the printing electromagnet are closed so much the earlier.

The rings 84, 85, 86, and 87 are adapted to rock a crank 118 downward. The said crank is provided with an upright arm 118' the upper end of which is engaged in a slot 70' made in the type wheel locking pawl 70. Therefore whenever a key is depressed, the pawl 70 which normally locks the type wheel against rotation is rocked into releasing position, so that the type wheel can be rotated. The crank 118 has a rocking support in bearings 135 and 136, and it is normally held by a spring 119 in contact with an adjustable cushion 120, and is returned by the said spring into its position of rest, as soon as the rings which have rocked the crank have returned into their normal positions. Therefore also the pawl 70 is returned into initial position and, after the type wheel has returned into normal position, into locking engagement with the type wheel shaft. The cushion 120 can be set by being mounted on a screw bolt 120'. Thereby the end position of the arm 118' and the pawl 70 can be set in such a way, that the said pawl can not fall with its locking nose on the bottom of the notch made in the collar 69 nor slide on the said collar. Thereby the pawl gets into locking engagement without any noise, and when the type wheel is returning into initial position, friction of the type wheel shaft is prevented.

When depressing a key, the rocker plate 12 strikes on a setting ring 121 secured to a rod 122, so as to shift the said rod downward. The rod is jointed at its upper end to an arm 123 and at its lower end to a rocking lever 124. By the downward movement 70 of the arm 123 a letter spacing mechanism 126 of any known or preferred construction is thrown into operation, which mechanism is operatively connected with a spur gearing 125. Simultaneously, through the intermediary of setting rings 127 and 128 a bail 131 is rocked which has a rocking support on pivots 129 and 130, and which is located with its curved part adjacent to the fingers 83' of the arms 83. By the said bail the 80 arm 83 which before was shifted forward by the key being depressed and into position with its finger above the bail 131 is thrown into releasing position, so that the setting member 72 or 73 can be returned 85 by its spring 132 into inoperative position. Thereby the rings 84, 85, 86, and 87 and the contact springs controlled thereby are likewise returned into inoperative positions, together with all the parts controlled by the 90 electromagnets. It will readily be understood, that this returning operation is entirely independent of the key which may still be in depressed position. In the same way the letter spacing mechanism 126 advances the carriage, even if the key is still in depressed position.

As after throwing the arm 83 into releasing position the setting member 72 or 73 must first be returned into normal position 100 by the spring 132, and the contact springs which by their operation were bent remain a short time in contact with their terminals until they have assumed their straight form, and as on the other hand the type wheel is already moving toward the platen, when the arm 83 is being thrown into releasing position the letter is necessarily printed before the current is actually interrupted. If the current were interrupted before printing is completed, the type wheel would be rotated backward before reaching the platen, and printing would not be effected with sufficient force. But what would be most objectionable is that the correct character 115 would not be printed on the paper, because the type wheel would already have been turned into initial position or into an intermediate position. In my improved machine the breaking of the circuits is initiated during the printing operation, and it is retarded by the intermediate members 72, 73, or 84, 85, 86, 87, 108, 109, 110, and 111, which begin their return movements when the arm 83 is being released. Thereby the 120 moment at which the circuit is broken is made independent of the moment at which printing takes place. Of course, the current is interrupted within a very short time after printing, and this is exactly the desirable 130

result aimed at by me, and which consists in breaking the circuit immediately after printing but under no circumstances before printing. Therefore in my improved machine I am enabled to depress several of the keys and yet to operate other keys. After releasing the keys, the arms 83 are at once returned by their springs 84 into operative positions.

10 The space key has been indicated by the numeral 133. It is provided on a key lever 134. When depressing the space key 134 the lever 124 which is operatively connected with the spacing mechanism 126 is actuated 15 and the carriage advanced one space.

The horizontal arms of the setting members 72, 73 which are located above the rings 84, 85, 86, and 87 are bent laterally toward each other and in such a way, that the 20 longer arms of the setting members 73 are located above the shorter arms of the setting members 72, so that the ends of adjacent arms are disposed within the same radial plane. Thereby one half of the space which 25 would otherwise be necessary for disposing the ends of the arms is spared, which is a considerable advantage in constructing the machine. Thereby the machine requires less space, and the size of the movable parts is 30 reduced, so that they are more easily moved, and by reducing the masses of the movable parts their speed and therefore the speed of the machine are increased.

In order that the type wheel may readily 35 be mounted on or dismounted from the type wheel shaft, I prefer to construct the same in the manner shown in Figs. 3 and 15. To the upper end of the type wheel shaft 7 a sleeve 137 is secured, which is made integral 40 with a transverse block 138 which is provided at one of its ends with an upright pin 140. Above the block 138 a spring 139 is coiled around the sleeve 137. The part 45 of the sleeve which is located above the plate is adapted to receive the type wheel which for this purpose is formed with a central sleeve 6. The upper part of the sleeve 137 is provided with two longitudinal slits 6² which are diametrically opposite to 50 each other, and within the said part of the sleeve a U-shaped spring 141 is embedded which is made at the upper ends of its shanks in the form of locking pawls 142 which are pointed at their top ends. Both 55 locking pawls are located symmetrically of the axis of the sleeve, and they project laterally of the slits 6². Above the locking pawls a push button 143 is located within the sleeve which projects upward and beyond the upper margin of the sleeve and is 60 formed at its bottom end with a notch 144 engaged by the upper points of the locking pawls. The locking pawls have the tendency to spring outward, and the beveled 65 faces on which the button 143 bears force

the latter upward, the said button being prevented from falling by an inner flange 137' formed at the top end of the sleeve 137 and engaging above a shoulder provided on the button 143.

70

To secure the type wheel on the shaft 7 it is placed on the upper part of the sleeve and turned, until the pin 140 engages in a hole made in the bottom part of the wheel, whereupon the type wheel is pressed downward. Thereby the locking pawls 142 yield at first backward and into the sleeve by their spring action, and the spring 139 is pressed together, but finally the pawls spring backward so as to engage above the 80 upper surface of the type wheel, whereupon the type wheel can be released and is forced by the spring 139 against the locking pawls. If it is desired to take the type wheel away from the shaft 7, the button 143 is slightly 85 depressed. Thereby the pawls are forced into the sleeve by reason of the beveled faces, so that the type wheel is released and forced upward by the spring 139, whereupon it can easily be removed.

90

Instead of the locking pawls shown in the drawing a spring member having a single locking pawl may be provided, or if desired more than two locking spring members may be employed. Furthermore instead of 95 mounting the locking pawls on rocking spring arms, they may be disposed in any suitable way, provided they are adapted to yield by spring action.

95

As has been stated above, the carriage is 100 shifted for letter spacing by means of the spacing mechanism 126 whenever the rod 122 is pulled downward either by the armature of the printing electromagnet or by depressing the key 133. It is necessary to limit 105 the movement of the carriage at both ends in order to fix the margin and the end of the line. In my machine two slide members 145 and 146 are provided for this purpose, which are mounted on a rack 147 connected 110 with the carriage and provided with scale marks. For setting the left hand margin or the beginning of the line the slide 145 is used, which is provided at its bottom side with a nose 148, coöperating with a pin 149 115 projecting through the top plate of the frame and adapted to be engaged at its left side by the nose 148. Also the slide 146 co-operates with the pin 149, and it is arranged in position for stopping the paper carriage 120 on its movement to the left. For this purpose the construction is such, that the circuit which connects the electromagnets and the terminals thereof is interrupted when the slide 146 strikes against the pin 149. The 125 pin 149 is disposed on a bell crank lever 150 which is disposed below the top plate 3 and carries on its downwardly projecting arm a pressure roller 151. The pressure roller bears on a contact spring 152 which is se- 130

cured to a pillar 153 rising from the lower base plate 1 and insulated therefrom. The lower end of the contact spring is disposed between two contact screws 154 and 155 which are secured to and insulated from a bracket 156 mounted on the pillar 153, and which are electrically connected with each other.

Normally the spring 152 bears on the contact screw 154 so that the circuit is closed. When the slide 146 strikes with its left hand lower edge 146' on a beveled face 149' formed on the right hand side of the pin 149, the pin is forced downward so as to rock the lever 150. Thereby the pressure roller 151 forces the contact spring 152 away from the contact screw 154 to such an extent, that it is held at a distance between both contact screws 154 and 155. Now the circuit is interrupted, so that the carriage can not be moved, nor the type wheel rotated nor thrown against the platen, when other key levers are depressed.

Now it frequently happens, that at the end of a line a few letters must be printed in order to complete a syllable. In order that this can be done in my improved machine, the contact screw 155 is provided. The bell crank lever 150 is mounted on a rock shaft 157 which extends to the front and upper part of the machine casing, where it is equipped with a crank 158. If the shaft is rocked by means of the crank beyond its intermediate position between contact screws 154 and 155 the contact spring engages the contact screw 155. Thereby the circuit which before was interrupted by the pin 149 being depressed by the slide 146 is again closed. When returning the slide the pin 149 is again released, and the contact spring returns into normal position and into engagement with the contact screw 154.

Furthermore, by returning the crank 158 the stop pin 149 can be retracted and the carriage shifted so far to the right, that the left hand slide 145 moves above the pin. Thereupon the left hand margin can be printed upon. When thus writing on the margin the slide 145 is moved with the carriage to the left and toward the pin 149, which has returned into advanced position, and when it strikes with its left hand lower part on the pin 149, the circuit is broken, so that the remarks made on the margin are not continued beyond the left hand marginal line of the ordinary line. When shifting the carriage and the slide 145 to the left the nose 148 slides with its beveled left hand face over the pin, whereupon the slide and the carriage are in their normal positions.

The electrical connection between the rotating electromagnets 58, 59, the printing electromagnets 37, and the individual contacts is shown in a diagrammatical way in Fig. 18. As appears from the description

of the machine, by depressing a key at first the contact of the coöperating rotating electromagnet 58 or 59 is moved in circuit closing position, whereupon by the armature of the said electromagnet the contact of the printing electromagnet 37 is moved in circuit closing position, so that both electromagnets are successively energized, and the type wheel performs at first its rotary movement and thereafter the throwing or printing movement. The return movement of the printing electromagnet is not retarded, the speed of writing is increased, and the character which has been printed can not be blurred by the type wheel starting its return rotary movement prior to the return movement away from the platen, for which purpose the rotating electromagnet is de-energized simultaneously with the printing electromagnet, so that no force acts on the type wheel during its return movement which could stop any of its movements. For this purpose at the side of the contact screws 113 and 115 contact screws 113' and 115' respectively are provided, which are connected with each other by a conductor X and coöperate with the contact springs 109 and 111.

For connecting the machine with the source of electric energy two terminals are provided on an insulating block 159 to which conductors I and V are connected. The conductor I includes the contact spring 152 mounted on the pillar 153 and leads to a connecting block 160, to which further conductors II, VI, and XI are connected, which conductors are constantly connected with one another and with the conductor I. According as the rotating electromagnet 58 or the rotating electromagnet 59 is to be thrown into operation by the key being depressed, the following circuits are made:

When depressing a key which controls the rotating electromagnet 58, at first the contact spring 111 is lifted which moves the contact 115 and 115' into position for closing the circuits controlled thereby. Thereby the following circuit is closed: from the + terminal, over I, 160, II, 58, III, 115, 111, IV, V, and back to the - terminal. The armature of the electromagnet 58 which is being attracted rocks the lever 116 with its contact screw 114 toward the contact spring 110. Thereby a circuit is closed from the + terminal, over I, 160, VI, 110, 114, 116, VII, VIII, printing electromagnet 37, IX, 115', 111, IV, V, and back to the - terminal, so that also the printing electromagnet is energized. As both circuits include the contact spring 111, they are simultaneously broken by the said contact spring. Similar connections are made in case a key is being depressed which controls the rotating electromagnet 59. When depressing such a key, the contact

spring 109 closes a circuit at the contacts 113 and 113'. Thereupon the current passes from the + terminal, over I, 160, XI, 59, XII, 113, 109, V, and to the - terminal.

5 As the armature of the electromagnet 59 is being attracted, the contact 108, 112, is closed, whereupon a second circuit is made as follows: from + terminal, over I, 160, VI, XIII, 108, 112, 117, VIII, printing electromagnet 37, IX, X, 113', 109, V, and back to the - terminal. Thereby also the printing electromagnet is thrown into operation, and if thereafter the contact spring 109 is retracted from the contact screws 113, 113', 10

15 the printing and rotating electromagnets are simultaneously deenergized. Thereby the return movement of the type wheel into position of rest is accelerated, and the speed of writing increased, and the letter which has been printed can not be blurred by the 20 type wheel beginning its return rotary movement before being moved out of contact with the paper.

In the claims the contacts 113' and 115' 25 are referred to as main circuit making and breaking means for the electrical throwing means, and the contacts 112 and 114 are described as additional circuit making and breaking means. The main circuit making 30 and breaking means or contacts 113' and 115' are controlled by the same operating members 109 and 111 respectively as the circuit making and breaking means 113 and 115 which control the electrical turning 35 means for the type carrier, so that the electrical turning and throwing means are simultaneously made inoperative, and the rotary return movement of the type carrier into initial position is not started before 40 the return movement of the type carrier away from the platen has been started.

I claim herein as my invention:

1. In a typewriting machine, the combination with the platen, and a rotatable type 45 carrier having circumferentially arranged types, of means for turning the type carrier with one of the types in printing position, means for throwing the type carrier toward the platen, means for operating the turning 50 means, means controlled by said turning means for operating the throwing means, means for simultaneously throwing said turning and throwing means out of operation, and means to return the type carrier 55 into initial position.

2. In a typewriting machine, the combination with the platen, and a rotatable type carrier having circumferentially arranged types, of means for turning the type carrier 60 with one of the types in printing position, means for throwing the type carrier toward the platen, means for operating the turning means, means controlled by said turning means for operating the throwing 65 means, means independent of the operating

means for the throwing means for simultaneously throwing said turning and throwing means of operation, and means to return the type carrier into initial position.

3. In a typewriting machine, the combination with the platen, and a rotatable type carrier having circumferentially arranged types, of power operated means for turning the type carrier with one of the types in printing position, power operated means for 70 throwing the type carrier toward the platen, means for throwing the power operated turning means into operation, means controlled by said turning means for throwing said power operated throwing means into 75 operation, means for simultaneously throwing said power operated turning and throwing means out of operation, and means to return the type carrier into initial position.

4. In an electrical typewriting machine, 80 the combination with the platen, and a type carrier having circumferentially arranged types, of electrical means for turning the type carrier with one of the types in printing position, electrical means for throwing 85 the type carrier against the platen, circuit making and breaking means for the electrical turning means, main circuit making and breaking means for the electrical throwing means, common operating means for the circuit making and breaking means for the 90 turning and throwing means, additional circuit making and breaking means for said throwing means arranged in series with the first named circuit making and breaking 95 means for the throwing means, means operative after said common operating means for operating said additional circuit making and breaking means, and means for returning the type carrier into initial position. 100

5. In an electrical typewriting machine, the combination with the platen, and a type carrier having circumferentially arranged types, of electrical means for turning the type carrier with one of the types in printing position, electrical means for throwing the type carrier against the platen, circuit making and breaking means for the electrical turning means, main circuit making and breaking means for the electrical throwing means, common operating means for the circuit making and breaking means for the turning and throwing means, additional circuit making and breaking means for said throwing means arranged in series with the first named circuit making and breaking 110 means for the throwing means and controlled by the electric turning means, and means for returning the type carrier into 115 initial position.

6. In a typewriting machine, the combination with the platen, and a rotatable type carrier having circumferentially arranged types, of power operated means for turning the type carrier with one of the types 120

- in printing position, power operated means for throwing the type carrier toward the platen, means for first throwing the power operated turning means and thereafter the power operated throwing means into operation, mechanical means for simultaneously rendering both power operated means inoperative, hand operated means for throwing said power operated means into operation, automatic means operative upon the actuation of the type carrier to disconnect said hand operated means, and means for returning the type carrier into initial position.
7. In an electrical typewriting machine, the combination with the platen, and a type carrier having circumferentially arranged types, of electrical means for turning the type carrier with one of the types in printing position, electrical means for throwing the type carrier against the platen, circuit making and breaking means for the electrical turning means, main circuit making and breaking means for the electrical throwing means, common operating means for the circuit making and breaking means for the turning and throwing means, additional circuit making and breaking means for said throwing means arranged in series with the first named circuit making and breaking means for the throwing means and controlled by the electric turning means, hand operated means for throwing said circuit making and breaking means into operation, automatic means operative upon the actuation of the type carrier to disconnect said hand operated means and power operated means, and means for returning the type carrier into initial position.
8. In a typewriting machine, the combination with the platen, a type carrier having circumferentially arranged types, power operated means for turning the type carrier with either one of its types in printing position, power operated means for throwing the type carrier against the platen, and means for returning the type carrier into initial position, of mechanism for throwing said power operated means into operation comprising hand operated means, levers adapted to be rocked by said hand operated means, rocking members on said levers, rockers adapted to be shifted by the rocking members into positions for arresting the turning movement of the type-carrier, means adapted to be operated by a plurality of said rockers and to throw said power operated means into operation, and a member automatically operated upon operation of the power operated means to rock said rocking members out of operative position.
9. In an electrical typewriting machine the combination with a type carrier having circumferentially arranged types, a platen, electrical means for turning the type carrier
- rier with either one of the types in printing position, and electrical means for throwing the type carrier against the platen, of contact making devices for the electric turning and throwing means comprising contact carrying members one for the turning and one for the throwing means, slidable members for operating said contact carrying members, a plurality of hand operated members each adapted to actuate both said slidable members, means controlled by the electrical turning means and coöperating with the contact carrying member for the throwing means for closing the circuit of the electrical throwing means, and means for returning the type carrier into initial position.
10. In an electrical typewriting machine the combination with a type carrier having circumferentially arranged types, a platen, electrical means for turning the type carrier with either one of the types in printing position, and electrical means for throwing the type carrier against the platen, of contact making devices for the electric turning and throwing means comprising contact carrying rocking levers, slidable members for rocking said levers, hand operated means for actuating said slidable members, means controlled by the electrical turning means and coöperating with the contact carrying lever for the throwing means for closing the circuit of the electrical throwing means, and means for returning the type carrier into initial position.
11. In an electrical typewriting machine the combination with a type carrier having circumferentially arranged types, a platen, electrical means for turning the type carrier with either one of the types in printing position, and electrical means for throwing the type carrier against the platen, of contact making devices for the electric turning and throwing means comprising contact carrying rocking levers, slidable members for rocking said levers, hand operated means for actuating said slidable members, and means controlled by the electrical turning means and coöperating with the contact carrying lever for the throwing means for closing the circuit of the electrical throwing means, automatic and simultaneously operative means for throwing both electric means out of operation, and automatic means to return the type carrier into initial position.
12. In an electrical typewriting machine the combination with a type carrier having circumferentially arranged types, a platen, an electromagnet and its armature for turning the type carrier with either one of the types in printing position, and electrical means for throwing the type carrier against the platen, of contact making devices for the electromagnet and electric throwing means comprising contact carrying rocking levers, slidable members for rocking said levers,

- hand operated means for actuating said slide-
able members, and a contact making member
connected with the armature of the electro-
magnet and coöperating with the contact
5 carrying lever for the throwing means for
closing the circuit of the electrical throwing
means, and means for returning the type car-
rier into initial position.
13. In an electrical typewriting machine
10 the combination with a type carrier having
circumferentially arranged types, a platen,
an electromagnet and its armature for
turning the type carrier with either one of
the types in printing position, and elec-
trical means for throwing the type carrier
15 against the platen, of contact making de-
vices for the electromagnet and electric
throwing means comprising contact carry-
ing rocking levers, hand operated means for
20 actuating said rocking levers, and a contact
making member connected with the arma-
ture of the electromagnet and coöperating
with the contact carrying lever for the
throwing means for closing the circuit of
25 the electrical throwing means, and means
for returning the type carrier into initial
position.
14. In an electrical typewriting machine,
the combination with a platen, a type car-
rier having circumferentially arranged
30 types, electrical means for turning the type
carrier with either one of its types in print-
ing position, electrical means for throwing
the type carrier against the platen, and
means for returning the type carrier into
35 initial position, of mechanism for throwing
said electrical means into operation compris-
ing hand operated means, concentrically ar-
ranged slideable cylindrical members adapt-
40 ed to be actuated by said hand operated
means, a plurality of rocking contact levers
adapted to be simultaneously rocked by said
cylindrical members and provided respec-
tively for closing the circuits of the elec-
45 trical turning and throwing means, and
means to throw said electrical means out of
operation.
15. In an electrical typewriting machine,
the combination with the platen, a type car-
rier having circumferentially arranged
50 types, electrical means for turning the type
carrier with either one of its types in print-
ing position, electrical means for throwing
the type carrier against the platen, and
means for returning the platen into initial
55 position, of mechanism for throwing said
electrical means into operation comprising
hand operated means, a plurality of con-
centrically arranged slideable cylindrical
members adapted to be actuated by said
60 hand operated means and having extensions
in the form of strips, a plurality of rocking
contact levers engaged by said extensions
and adapted to be simultaneously rocked by
65 said cylindrical members and provided re-
spectively for closing the circuits of the elec-
trical turning and throwing means, and
means to throw said electrical means out of
operation.
16. In an electrical typewriting machine,
70 the combination with the platen, a type car-
rier having circumferentially arranged
types, double electrical means for turning
the type carrier one to the right and the
other one to the left and with either one of
75 its types in printing position, electrical
means for throwing the type carrier against
the platen, and means for returning the
platen into initial position, of mechanism
for throwing said electrical means into op-
80 eration comprising two pairs of concentri-
cally arranged slideable cylindrical members,
two sets of hand operated means adapted to
actuate each one of said pairs of cylindrical
members, two pairs of rocking contact levers
85 each pair adapted to be rocked by one of
said pairs of cylindrical members and pro-
vided for closing the circuits of the electric
throwing means and of one of the electrical
turning means, and means to throw said
90 electric turning and throwing means out of
operation.
17. In an electrical typewriting machine,
the combination with the platen, a type car-
rier having circumferentially arranged
95 types, double electrical means for turning
the type carrier one to the right and the
other one to the left and with either one of
its types in printing position, electrical
means for throwing the type carrier against
100 the platen, and means for returning the
platen into initial position, of mechanism for
throwing said electrical means into opera-
tion comprising two pairs of concentri-
cally arranged slideable cylindrical members, two
105 sets of hand operated means adapted to ac-
tuate each one of said pairs of cylindrical
members, two pairs of rocking contact levers,
each pair adapted to be rocked by one of
said pairs of cylindrical members and pro-
110 vided for closing the circuits of the electric
throwing means and of one of the electrical
turning means, a contact member adapted
to be operated by said electrical turning
means and coöperating with the contact
115 lever for closing the circuit of the electrical
throwing means, and means to throw said
electric turning and throwing means out of
operation.
18. In an electrical typewriting machine,
120 the combination with the platen, a type car-
rier having circumferentially arranged
types, double electrical means for turning
the type carrier one to the right and the
other one to the left and with either one of
125 its types in printing position, electrical
means for throwing the type carrier against
the platen, and means for returning the
platen into initial position, of mechanism
for throwing said electrical means into op-
130

- eration comprising two pairs of concentrically arranged slidable cylindrical members, two sets of hand operated means adapted to actuate each one of said pairs of cylindrical members, two pairs of rocking contact levers each pair adapted to be rocked by one of said pairs of cylindrical members and provided for closing the circuits of the electric throwing means and of one of the 10 electrical turning means, two contact members adapted to be operated respectively by said electrical turning means and coöperating respectively with the contact levers for closing the circuit of the electrical throwing 15 means, and means to throw said electric turning and throwing means out of operation.
19. In an electrical typewriting machine, the combination with the platen, a type carrier having circumferentially arranged types, electrical means for turning the type carrier with either one of its types in printing position, electrical means for throwing the type carrier against the platen, and 20 means for returning the type carrier into initial position, of mechanism for throwing said electrical means into operation comprising hand operated means, concentrically arranged slidable cylindrical members adapted to be actuated by said hand operated means, rocking members connected one with each of said cylindrical members for 25 guiding the same and mounted on the same axis, rocking contact levers adapted to be simultaneously rocked by said cylindrical members and provided respectively for closing the circuits of the electrical turning and throwing means, and means to throw said electrical means out of operation.
20. In an electrical typewriting machine, the combination with the platen, a type carrier having circumferentially arranged types, double electrical means for turning the type carrier one to the right and the other one to the left and with either one of its types in printing position, electrical means for throwing the type carrier against the platen, and means for returning the platen into initial position, of mechanism 45 for throwing said electrical means into operation comprising two pairs of concentrically arranged slidable cylindrical members, rocking members connected one with each of said cylindrical members for guiding the same and mounted on the same axis, two sets of hand operated means adapted to actuate each one of said pairs of cylindrical members, two pairs of rocking contact levers each pair adapted to be rocked by one of 50 said pairs of cylindrical members and provided for closing the circuits of the electric throwing means and of one of the electrical turning means, and means to throw said electrical turning and throwing means out 55 of operation.
21. In an electrical typewriting machine, the combination with the platen, a type carrier having circumferentially arranged types, power operated means for turning the type carrier with either one of its types in printing position, electrical means for throwing the type carrier against the platen, and means for returning the platen into initial position, of mechanism for throwing said electrical means into operation comprising hand operated means, concentrically arranged slidable cylindrical members adapted to be actuated by said hand operated means and having extensions in the form of strips, rocking members connected 70 with strips of each of said cylindrical members for guiding the same and mounted on the same axis, two sets of hand operated means adapted to actuate each one of said pairs of cylindrical members, two pairs of 75 rocking contact levers, each pair adapted to be rocked by one of said pairs of cylindrical members and provided for closing the circuits of the electric throwing means and of one of the electrical turning means, and means to throw said electric turning and throwing means out of operation.
22. In a typewriting machine, the combination with the platen, and a rotatable type carrier having circumferentially arranged types, of power operated means for turning the type carrier with one of the types in printing position, power operated means for throwing the type carrier toward the platen, operating means one for each of 85 said power operated means, a plurality of hand operated means each adapted to actuate both operating means, stop members controlled by the hand actuated means and adapted to arrest the type carrier in different rotary positions relatively to the platen, the operating means for the power operated turning means, means to throw said power operated means out of operation, and means to return the type carrier, operating means, hand operated 90 means and stop members into normal positions.
23. In a typewriting machine, the combination with the platen, and a rotatable type carrier having circumferentially arranged types, of power operated means for turning the type carrier with one of the types in printing position, power operated means for throwing the type carrier toward the platen, operating means one for each of said power 100 operated means, a plurality of hand actuated means each adapted to actuate both operating means, stop members controlled by the hand actuated means and adapted to arrest the type carrier in different rotary positions.

- relatively to the platen, the operating means for the power operated means being so disposed relatively to the hand operated means that the operating means for the power operated throwing means are engaged after the operating means for the power operated turning means and that the strokes after which the hand actuated means engage the operating means for the throwing means are different for the individual hand actuated means, means to throw said power operated means out of operation, and means to return the type carrier, operating means, hand actuated means and stop members into normal positions.
24. In a typewriting machine, the combination with the platen, and a rotatable type carrier having circumferentially arranged types, of power operated means for turning the type carrier with one of the types in printing position, power operated means for throwing the type carrier toward the platen, operating means respectively controlling said power operated means, a plurality of hand operated means each adapted to actuate both operating means, stop members controlled by the hand actuated means and adapted to arrest the type carrier in different rotary positions relatively to the platen, the operating means for the power operated means being so disposed relatively to the hand operated means that the operating means for the power operated throwing means are engaged after the operating means for the power operated turning means, simultaneously operative means to throw both said power operated means out of operation, and means to return the type carrier, operating means, hand operated means and stop members into normal positions.
25. In a typewriting machine, the combination with the platen, and a rotatable type carrier having circumferentially arranged types, of power operated means for turning the type carrier with one of the types in printing position, power operated means for throwing the type carrier toward the platen, operating means respectively controlling said power operated means, a plurality of hand operated means each adapted to actuate both operating means, stop members controlled by the hand actuated means and adapted to arrest the type carrier in different rotary positions relatively to the platen, the operating means for the power operated throwing means and the strokes after which the hand operated means engage the operating means for the throwing means are different for the individual hand operated means, means to throw said power operated means out of operation, and means to return the type carrier, operating means, hand operated means and stop members into normal positions.
26. In an electrical typewriting machine, the combination with the platen, and a rotatable type carrier having circumferentially arranged types, of electrical means for turning the type carrier with one of the types in printing position, electrical means for throwing the type carrier toward the platen, operating means for each of the electrical means, a plurality of hand operated means each adapted to actuate both operating means, stop members controlled by the hand actuated means and adapted to arrest the type carrier in different rotary positions relatively to the platen, the operating means for the electrical means being so disposed relatively to the hand operated means that the operating means for the electrical throwing means are engaged after the operating means for the electrical turning means, means to throw said power operated means out of operation, and means to return the type carrier, operating means, hand operated means and stop members into normal positions.
27. In an electrical typewriting machine, the combination with the platen, and a rotatable type carrier having circumferentially arranged types, of electrical means for turning the type carrier with one of the types in printing position, electrical means for throwing the type carrier toward the platen, operating means respectively controlling said electrical means, a plurality of hand operated means each adapted to actuate both operating means, stop members controlled by the hand actuated means and adapted to arrest the type carrier in different rotary positions relatively to the platen, the operating means for the electrical means being so disposed relatively to the hand operated means that the operating means for the electrical throwing means are engaged after the operating means for the electrical turning means and that the strokes after which the hand operated means engage the operating means for the throwing means are different for the individual hand operated means, means to throw said electrical means out of operation, and means to return the type carrier, operating means, hand operated means and stop members into normal positions.
28. In an electrical typewriting machine, the combination with the platen, and a rotatable type carrier having circumferentially arranged types, of electrical means for turning the type carrier with either one of the types in printing position, electrical means for throwing the type carrier toward the platen, operating means respectively controlling the electrical means, a plurality of hand operated means each adapted to actuate both operating means, stop members controlled by the hand actuated means and adapted to arrest the type carrier in different rotary positions relatively to the platen, the operating means for the electrical means being so disposed relatively to the hand operated means that the operating means for the electrical throwing means are engaged after the operating means for the electrical turning means and that the strokes after which the hand operated means engage the operating means for the throwing means are different for the individual hand operated means, simultaneously operative means to throw said power operated means out of operation, and means to return the type carrier, operating means, hand operated means and stop members into normal positions.

- of hand operated means each adapted to actuate both operating means, stop members controlled by the hand actuated means and adapted to arrest the type carrier in different rotary positions relatively to the platen, the operating means for the electrical means being so disposed relatively to the hand operated means that the operating means for the electrical throwing means are engaged after the operating means for the electrical turning means, simultaneously operative means to throw said electrical means out of operation, and means to return the type carrier, operating means, hand operated means, and stop members into normal positions. 5
29. In an electrical typewriting machine, the combination with the platen, and a rotatable type carrier having circumferentially arranged types, of electrical means for turning the type carrier with one of the types in printing position, electrical means for throwing the type carrier toward the platen, operating means respectively controlling said electrical means, a plurality of hand operated means each adapted to actuate both operating means, stop members controlled by the hand actuated means and adapted to arrest the type carrier in different rotary positions relatively to the platen, the operating means for the electrical means being so disposed relatively to the hand operated means that the operating means for the electrical throwing means are engaged after the operating means for the electrical turning means and that the strokes after which the hand operated means engage the operating means for the throwing means are different for the individual hand operated means, simultaneously operative means to throw said electrical means out of operation, and means to return the type carrier, operating means, hand operated means and stop members into normal positions. 20
30. In an electrical typewriting machine, the combination with the platen, and a type carrier having circumferentially arranged types, of electrical means for turning the type carrier with one of the types in printing position, electrical means for throwing the type carrier against the platen, circuit making and breaking means for the electrical turning and throwing means, a plurality of concentric rings respectively controlling said circuit making and breaking means and one of them having its end face substantially in the form of a screw-thread, a plurality of hand operated members disposed around said rings and each adapted to engage said end faces of the rings so as to successively operate the rings, and means to return, said type carrier, circuit making and breaking means, and rings into initial positions. 45
31. In an electrical typewriting machine, the combination with the platen, and a type carrier having circumferentially arranged types, of electrical means for turning the type carrier with one of the types in printing position, electrical means for throwing the type carrier toward the platen, means for throwing the power operated turning means and the power operated throwing means into operation, means for rendering both power operated means inoperative, and means for 60
- carrier having circumferentially arranged types, of electrical means for turning the type carrier one to the right and the other one to the left and with either one of the types in printing position, electrical means for throwing the type carrier against the platen, circuit making and breaking means for the electrical turning and throwing means, two pairs of concentric rings the rings of each pair respectively controlling the circuit making and breaking means for the electrical turning and throwing means and one ring of each pair having its end face substantially in the form of a screw-thread, a plurality of hand operated members disposed around said rings and alternately adapted to engage the end faces of the rings of the inner and outer pairs so as to successively operate the rings of each pair, and means to return said type carrier, circuit making and breaking means and rings into initial positions. 70
32. In an electrical typewriting machine, the combination with the platen, and a type carrier having circumferentially arranged types, of electrical means for turning the type carrier one to the right and the other one to the left and with one of the types in printing position, electrical means for throwing the type carrier against the platen, circuit making and breaking means for the electrical turning and throwing means, two pairs of concentric rings the rings of each pair respectively controlling the circuit making and breaking means for the electrical turning and throwing means and one ring of each pair having its end face substantially in the form of a screw-thread, a plurality of hand operated members disposed around said rings and alternately adapted to engage the end faces of the rings of the inner and outer pairs so as to successively operate the rings of each pair, adjacent hand operated members being disposed with their engaging ends substantially within the same radial plane, and means to return said type carrier circuit making and breaking means and rings into initial positions. 80
33. In a typewriting machine, the combination with the platen, and a type carrier having circumferentially arranged types and disposed on a rotatable shaft, a locking member in nose and notch engagement with the shaft and adapted to lock the shaft and type carrier in medial position, and hand operated means for throwing said locking member in nonlocking position, of power operated means for turning the type carrier with one of the types in printing position, power operated means for throwing the type carrier toward the platen, means for throwing the power operated turning means and the power operated throwing means into operation, means for rendering both power operated means inoperative, and means for 100

returning the type carrier into initial position.

34. In a typewriting machine, the combination with the platen, and a type carrier having circumferentially arranged types and disposed on a rotatable shaft, a locking member in nose and notch engagement with the shaft and adapted to lock the shaft and type carrier in medial position, and hand operated means for throwing said locking member in non-locking position, of power operated means for turning the type carrier with one of the types in printing position, power operated means for throwing the type carrier toward the platen, means for first throwing the power operated turning means and thereafter the power operated throwing means into operation, means for simultaneously rendering both power operated means inoperative, and means for returning the type carrier into initial position.
35. In an electrical typewriting machine, the combination with the platen, a type carrier having circumferentially arranged types, a shaft supporting said type carrier and having a notched collar, a rocking lever normally engaging said collar and holding the shaft and carrier in a medial position,

electrical means for turning the type carrier with either one of its types in printing position, electrical means for throwing the type carrier against the platen, and means for returning the type carrier into initial position, of mechanism for throwing said electrical means into operation comprising hand operated means, concentrically arranged slideable cylindrical members adapted to be actuated by said hand operated means, an operative connection between one of said cylindrical members and the rocking lever and adapted to throw said rocking lever in non-locking position, rocking members connected one with each of said cylindrical members for guiding the same and mounted on the same axis, rocking contact levers adapted to be rocked by said cylindrical members and provided respectively for closing the circuits of the electrical turning and throwing means, and means to throw said electrical means out of operation.

In testimony whereof I hereunto affix my signature in the presence of two witnesses.

OSKAR FISCHER.
